By Attorney.

UNITED STATES PATENT OFFICE.

JEAN MARIE LOUIS ANTOINE AUBERT, OF PARIS, FRANCE.

RIVER DAM.

Application filed January 23, 1926, Serial No. 83,321, and in France May 2, 1925.

This invention relates to improvements in gates for use in movable river dams and more particularly in gate sections or plates equipped with slide blocks.

5 In the accompanying drawings, Figures 1, 2 and 3 show a pivotally-mounted gate constructed in accordance with my invention. Fig. 1 is a vertical section and Fig. 2 a perspective view showing the gate in raised position. Fig. 3 is a vertical section and Fig. 4 a plan view showing the gate in lowered position.

Figs. 5, 6 and 7 relate to the slide block element of my invention. Fig. 5 is a plan view, Fig. 6 a longitudinal section on the line 6—6 of Fig. 5, and Fig. 7 a transverse section on the line 7—7 of Fig. 5 or Fig. 6.

My invention relates to a gate section or plate 1 for river dams, which is provided 20 with a special slide block 4 of the character subsequently described and is characterized by a special construction of the bottom part of the plate and the ground sill 7. The aforesaid plate 1 (Figs. 1—4) is pivoted to 25 the upper horizontal axis 1' of a support 2 which, in turn is pivoted at its lower end 8 to the sill 7, and strut 3 is also pivoted to the said axis 1' and rests upon the slide block 4. This block is provided with a locking notch 30 5 and a vertical guide rib or shoulder 5', the upper edge of the rib sloping downward to the bottom of notch 5 in such a manner that the strut 3 will slide upon it; and at one side of the notch 5 and rib 5' a longitudinal 35 channel 6 is formed (Figs. 5—7).

In my invention, the bottom part of the gate section or plate 1 is made longer than in the known types, and it rests upon the ground sill 7 even when the plate lies flatwise. The upper part of the sill has substantially the form of a cylinder whose horizontal axis coincides with the lower axis 8 of the support 2, so that I am thus 40 enabled to raise and lower the plate by traction which is exerted exclusively from the upstream side upon the top of the plate.

To facilitate the lifting and lowering operations, the top of each plate or gate section is provided with a chain 9 (Fig. 4), and 45 the ends of all the chains 9 are connected together by chains 10. To prevent the chains 9 from catching upon the top of the plate, the upper edge of the plate is beveled; and in order to prevent an obstacle situated in 50 front of the sill from interfering with the

lifting operation, the lower edge of the plate is also beveled.

The lifting operation is as follows:

The plate being in the flat position shown in Figs. 3 and 4, the chain 9 is seized and an upward traction is exerted from the upstream side. Due to the relative positions of the plate 1 and the sill 7, the plate will slide upon the sill during the movement of lifting, and upon completion of this movement the strut 3 will drop into the notch 5 in block 4 and thus lock the entire device; the lower end of the strut following the straight path *a—b*, Fig. 5. By the use of the small chains 10 connecting the chains 9, 65 70 it will be an easy matter, after a plate has been lifted, to seize the chain of the next plate since the end of that chain is now out of the water. To readily grasp the chains of the plates situated at the ends of 75 the dam, I attach to them suitable chains (not shown) whose other ends are fastened in the side walls of the dam.

The lowering operation is as follows:

The plate being in the raised position 80 shown in Figs. 1 and 2, an upward traction is exerted upon the chain 9 from the upstream side, thus releasing the strut end from its notch 5 and allowing it to slide across the inclined surface leading to rib 85 5' and drop over the edge of said rib into the channel 6 in the slide block. The apparatus is now left to itself, and the plate 1 will take the inclined position, while the strut will follow the channel and will lie 90 flat as shown in Fig. 3; the complete path of the strut end being indicated by the line *b—c—d—e—f—a*.

It will be observed that, due to the special arrangement of the bottom of the plate and of the ground sill, the said plate can be raised and lowered by traction on the top of the plate which is exerted solely from the upstream side, and without obliging the plate to pass through an intermediate tilted 95 position, so that the operations can be readily performed in all cases, provided a sufficiently powerful cable winch is employed.

I claim as my invention:

1. In a river dam, the combination of a 105 plurality of gate sections, an individual support for each section pivoting at its lower end about a horizontal axis parallel to the dam, and a ground sill on which the gate sections bear at their lower edges; the upper 110

surface of the sill being cylindrical and co-axial with the pivotal axes of said supports so that the gate sections can swing with their supports while keeping their lower edges constantly in bearing contact with the sill, said sections being raisable simply by traction exerted upon their upper edges.

2. A construction according to claim 1, in which traction chains are connected to the tops of the gate sections, and in which the free ends of such chains are joined together by cross-chains; the opposite ends of the sections being beveled to prevent interference with the traction chains.

3. In a river dam, the combination of a ground sill having a cylindrical upper portion, a plurality of gate sections, a rocking

support for each section pivoted at its upper end to the under face thereof and at its lower end to the sill at a point coincident with the axis of curvature of the cylindrical portion of the sill to permit swinging movement of the section between a substantially upright position and a horizontal position consequent upon traction exerted upon the top of the section from the upstream side; said section having a length sufficient to enable it to rest upon the sill in both positions; a slide block for each section, and a strut pivoted at its upper end to each section and engageable at its lower end with the corresponding block.

In testimony whereof I affix my signature.

JEAN MARIE LOUIS ANTOINE AUBERT.
